STORE ENCLOSURE

Berger A. Peterson, Milton, Mass.

Application May 21, 1946, Serial No. 671,250

3 Claims. (Cl. 20—1.6)

1

This invention relates to a collapsible partition structure to be erected on the inside of stores and analogous locations to form an enclosure around a door or delivery opening so that goods may be delivered outside of the usual business hours without permitting the delivery crew to gain access to the interior of the store or the store proper. Such partitions are found in patents to C. O. Sherrill No. 1,924,963 and to Alfred G. Peterson Nos. 2,105,095 and 2,219,272, and the present invention may be considered an improvement over such structures.

The portable partitions or enclosures of the Sherrill type and also the types disclosed in patents issued to Alfred G. Peterson provide a barrier against admission or entrance to the store proper. However, they have not been found completely satisfactory because of costs, perplexity of structure for handling and failure to prevent undiscovered passage beyond such vestibule.

It is the object of the present invention to provide a simple enclosure at a reduced cost, susceptible of easy installation, and removable by a single individual due to its construction and light weight.

It is a further object of the invention to provide a structure which can be readily removed and stored and affords complete access to the area enclosed.

The foregoing and other objects and advantages of the present invention will become apparent in view of the following description taken in conjunction with the drawings, wherein:

Fig. 1 is a view in perspective of a collapsible partition embodying the features of the present invention shown installed on the inside of a store door;

Fig. 2 is a detailed view on an enlarged scale showing the method of attaching the frame of the partition to the store wall;

Fig. 3 is a detailed view on an enlarged scale showing the use of the T-shape rod to connect the partition to the floor;

Fig. 4 is a detailed view on an enlarged scale showing the method of connecting bracing elements of the frame to the floor of the store;

Fig. 5 is a detailed view on an enlarged scale of the construction of the forward corners of the supporting frame of the partition;

Fig. 6 is a detailed view showing a modified arrangement of the means of fixing the structure to the floor; and

Fig. 7 is a detailed view on an enlarged scale showing the eye-bolt fastening means and related

parts of the modified arrangement disclosed in Fig. 6.

Referring to the drawings, a portion of the wall 10 of a store has a door opening with doors 11 mounted therein. The partition proper preferably has walls of fabric, such as heavy duck or canvas, the side walls being indicated at 12 and 13 and the end wall being indicated at 14. The supporting framework comprises front posts 15 and 16 which at their upper ends are supported by attachments to the wall 10 by a bracket 17, the details of which are shown in Fig. 2. Posts 15 and 16 have a flattened perforated upper extremity for reception in the bifurcated extremity 18 for an upper horizontal connecting member 19 which is riveted thereto. The horizontal member 19 connects posts 15 and 16 and is so designed to rest flatly against the wall 10.

The frame is attached to wall 10 by means of 20 a bracket 17 riveted to a metal strap around the posts 15 and 16 thereby preventing movement of the forward portion of the framework in any direction.

The rear portion of the enclosure is supported 25 by posts 19 and 20 which at their upper ends project through the corners of the canvas covering and are anchored in the floor by plates 21. Chains or analogous members 22 extend along the bottom edges of the fabric side walls and are fastened to the posts 15, 16, 19, and 20 to 30 prevent lifting of said edges.

The top and rear flaps or panels 23 and 14 are provided with a fastening element preferably of the slide fastening or "zipper" type 24 to be 35 opened and closed by a slide element having a tab 25 and, if desired, provided with one or more auxiliary links. It will be noted that the slide fastener extends down the center of the top panel 23 and also down the entire length of the rear panel 14 closing and securely fastening the same by means of locking or attaching tab 25 to member 28.

The two sections of the rear panel 14 have a pair of brace chains or analogous members 22 40 sewn in the hems and these are fastened together when the said panel has been closed and locked down through the use of a securing member 28. The details of this connection are more clearly indicated in Fig. 3 being by means of an element 28 having a T-shaped end which is 45 inserted through the ends of the chains 22 and a link on tab 25 into the floor plate 29 and then turned at right angles. The rod is securely fastened to a ring attached to rear post 20 by a 50 snap hook 30. Said ring is placed at a point on

the said post outside the enclosure at a greater distance from the floor than the length of a human arm so that it cannot be unfastened from inside the enclosure.

Although the rod 28 may be used to accomplish the above-described function, the same result may be accomplished by the use of an eye pin 39 inserted through the ends of the chains 22 and a link attached to the tab 25 and screwed into the floor plate 40. Said pin is locked by a chain 31 or analogous flexible members fixed to post 19 and inserted through eye of the pin and securely fastened to post 20 by a snap hook 30.

The front portion of panel 23 is secured to the wall by means of sliding rings 32 over the cross member 18 thereby allowing the upper panel, when divided, to be gathered and rolled with the balance of the structure to either side of the door 11.

A means of ingress and egress is provided by a crescent shaped opening 33 in panel 12. This opening is securely closed when not in use by means of a slide fastening element of the type described above using two slide elements which converge at the center point 34 and are there fastened by the use of a padlock 35 on the inside of the enclosure.

The rear posts 19 and 20 are held in upright position with walls and top panels held taut by an adjustable guy element 36 hooked into floor plate 31 and tightened by turnbuckle 38.

Through the use of the above-described invention, the delivery man having a key to the store, may deposit his merchandise during times when the store is closed, retire and lock the door. Later the store operator may enter in the same manner and remove the lock from the crescent shaped opening and have access to the store proper where he may remove the entire partition by sliding forward the fastening member, dividing the closure into two parts, removing the supporting frame and rolling the entire closure into a compact bundle to be stored on each side of the doorway.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. A collapsible partition structure adapted to be mounted upon a supporting surface to enclose a portion of a room adjacent an outside entrance and comprising side, rear and top walls of flexible material, a removable corner post at the junction between each side and rear wall, each post having its lower extremity secured to said supporting surface, flexible members secured to the lower extremities of said side and rear walls and to said corner posts for maintaining the lower portions of said side and rear walls taut to prevent entrance therebeneath, a slide fastener including a slide member extending longitudinally of the top wall and from top to bottom of the rear wall to permit the structure to be separated into two parts for storage, and a rigid fastening member detachably connected with the supporting surface and locking the slide member of the slide fastener and the flexible member connected to the rear wall to the supporting surface.
2. Collapsible partition structure as set forth in claim 1 where said rigid fastening member comprises an eye-bolt passing through a link connected to the slide member of the slide fastener and through the flexible member secured to the rear wall, an extremity of said eye-bolt engaging said supporting surface, and locking means passing through the eye of said eye-bolt.
3. Collapsible partition structure as set forth in claim 2 where the locking means passing through the eye of said eye-bolt comprises a flexible member having the extremities thereof detachably secured to the corner posts associated with the rear wall of said partition structure.

BERGER A. PETERSON.
